U.S. PATENT DOCUMENTS

D. 426,166 * 6/2000 Ferron et al. D10/104

The ornamental design for a handheld electronic pet training transmitter, as shown and described.

DESCRIPTION

FIG. 1 is a perspective view of a handheld electronic pet training transmitter of the present invention;

FIG. 2 is a front elevation view thereof;

FIG. 3 is a rear elevation view thereof;

FIG. 4 is a left side elevation view, the right side elevation view being a mirror image thereof;

FIG. 5 is a top plan view thereof; and,

FIG. 6 is a bottom plan view thereof.

The broken lines are for illustrative purposes only and form no part of the claimed design.
